W. Lee Skelton

UNITED STATES PATENT OFFICE.

HARRY LEIGH CURRAN, OF NEW YORK, N. Y.

AUTOMOBILE RADIATOR SHIELD.

Application filed December 21, 1922. Serial No. 608,342.

My invention relates to means for shielding the front of an automobile radiator in cold weather and for adjusting the degree of exposure of the radiator fins to the direct action of the air.

The invention will be understood by reference to the accompanying drawing in which—

Fig. 1 is a front elevation of a radiator equipped with an embodiment of the invention.

Fig. 2 is a vertical sectional view of the device shown in the preceding figure, in conjunction with certain elements of the radiator, hood and cowl of an automobile, these latter elements being shown partly in section.

Fig. 3 is a perspective view of the two members comprising the device.

In the embodiment of my invention, I employ two primary parts, to wit, a frame member 1 and a slide plate 2, both being preferably formed of sheet metal. The frame member 1 comprises a flat plate formed with a series of horizontal parallel spaced apertures 3. At its side margins frame member 1 is bent inwardly upon itself and thence angularly at *b* and thence in the plane of the main body of the frame, as at *c*. The angularly bent members *b* and *c* afford guiding means for the slide plate 2. The frame, with its attached slide plate, is placed upon the outer surface of the radiator and attaching bolts 5 are run between the fins of the radiator and to the opposite face thereof, where they are held by nuts 6.

The slide plate may be automatically operated by the usual thermostatic control known to the art, but I prefer that the simple and effective manual operating means shown in the drawings be employed. This means consists of a spring 7 attached to the radiator shell at one end and to the slide plate at 8, the spring normally holding the slide plate in such position that its spaced apertures lie in register with the corresponding apertures of the frame; and at the top of the slide plate I attach a flexible cable 9 which I pass through the radiator fins and extend to a point beyond the dashboard 10 through the instrumentality of a pull rod 10, the latter being provided with a handle.

The lateral face of the pull rod is formed with notches 10^x adapted to be engaged by a friction pin 12, the pressure of a spring B upon the pin causing the latter to exert sufficient frictional pressure against the notches of the pull rod to hold the slide plate in the position to which it is adjusted and against the pull of spring 7.

The invention comprises means for sealing the shield against the passage of air between the slide plate and the frame when the slide is adjusted to closed position, which would otherwise occur between the upper and lower edges of the bars 14 of the slide plate and the bars 14_x of the frame. To this end I turn in or inwardly flange the top of each slide plate bar 14 and turn out or outwardly flange the top edge of each bar 14_x of the frame. When the slide plate is in closed position the inturned upper flange *f* of each bar 14 lies immediately under and in contact with the lower edge of a bar 14_x of the frame, and the outturned flange *g* of each bar 14_x of the frame closely engages the lower inner face of a bar 14 of the slide plate.

It will be understood that variations in the embodiment illustrated in the drawings are considered as within the spirit of my invention, what I claim and desire to secure by Letters Patent being as follows:

In a radiator shield, a frame comprising a flat plate carrying on opposed edges guiding means, said plate being formed with a series of parallel apertures, and a slide plate held in position upon the frame by said guiding means and formed with a series of apertures parallel with the apertures of the frame, means whereby the slide plate may be moved so that its apertures will lie in register with those of the frame or in position to close the apertures of the frame, a flange formed on the slide plate parallel and contiguous to each of its said apertures, and a flange on the frame contiguous to and parallel with each of the apertures therein, the said flanges co-acting to seal the said apertures against the admission of air when the slide plate is in closed position.

HARRY LEIGH CURRAN.
